UNITED STATES PATENT OFFICE.

THEODORE F. KOTTER, OF HOLLIS, NEW YORK.

DESIGN FOR A TOY CLOWN.

Application filed March 30, 1923. Serial No. 5,645. Term of patent 3½ years.

To all whom it may concern:

Be it known that I, THEODORE F. KOTTER, a citizen of the United States, residing at Hollis, Long Island, New York, have invented a new, original, and ornamental Design for a Toy Clown, of which the following is a specification, reference being had to the accompanying drawing, forming a part thereof.

The figure of the drawing is a view in front elevation of a toy intended to represent a clown with the features and different portions of the clothing of the clown contrastingly colored.

I claim—

The ornamental design for a toy clown as shown and described.

In witness whereof I have hereunto signed my name this 1st day of March, 1923.

THEODORE F. KOTTER.
